FOREIGN PATENT DOCUMENTS

DE 29824838 U1 4/2003

* cited by examiner

Primary Examiner — George D. Kirschbaum*Assistant Examiner* — Antoinette Martine Suiter(74) *Attorney, Agent, or Firm* — Sand, Sebolt & Wernow Co., LPA(57) **CLAIM**

The ornamental design for an adjustable gauge block, as shown and described.

DESCRIPTION

FIG. 1 is a top front perspective view of the adjustable gauge block in accordance with my design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof;

FIG. 7 is a bottom plan view thereof; and,

FIG. 8 is an alternative top front perspective view thereof.

The broken lines illustrate portions of the adjustable gauge block which form no part of the claimed design.
